Primary Examiner — Keli L Hill*(74) Attorney, Agent, or Firm* — Goudreau Gage Dubuc; Gwendoline Bruneau(57) **CLAIM**

The ornamental design for a tool head, as shown and described.

DESCRIPTION

FIG. 1 is perspective view of the tool head;

FIG. 2 is a first side view of the tool head of FIG. 1;

FIG. 3 is a bottom view of the tool head of FIG. 1;

FIG. 4 is a top view of the tool head of FIG. 1;

FIG. 5 is a second side view of the tool head of FIG. 1;

FIG. 6 is a back view of the tool head of FIG. 1; and,

FIG. 7 is a front view of the tool head of FIG. 1.

The broken line is included for the purpose of illustrating environmental structure and forms no part of the claimed design.
